(57) **CLAIM**

The ornamental design for a frame for commode chair as shown and described.

DESCRIPTION

1. Frame for commode chair

1.1 : Perspective

1.2 : Perspective

1.3 : Front

1.4 : Back

1.5 : Left

1.6 : Right

1.7 : Top

1.8 : Bottom

1.9 : Perspective view shown in use with the chair

The broken lines in the reproductions depict portions of the frame for commode chair that form no part of the claimed design; The broken lines in FIG. 1.9 depict environmental structure of the frame for commode chair that form no part of the claimed design.

1 Claim, 9 Drawing Sheets
